UNITED STATES PATENT OFFICE

EUGÈNE BRANDT, OF GENEVA, SWITZERLAND

RAILROAD CONSTRUCTION

Application filed April 10, 1931, Serial No. 529,266, and in Switzerland January 24, 1931.

This invention relates to a railroad construction and has as its particular object to provide a rail for railroads which is of heavier and more resistant construction than the rails as at present in use.

Another object is the provision of a rail joint which is less subject to wear than the usual fish-plate connections and which avoids perforation of the rails for inserting connecting bolts.

A further object is the provision of resilient fastening means for securing the rails to the ties and to avoid the use of screw bolts and nuts with their disadvantages which are well known in the art.

With these and other objects in view the invention consists in the novel form, combination and arrangement of parts as will be hereinafter described, reference being had to the accompanying drawings, in which

Figure 1 is a plan view of a rail forming a part of the railroad according to the invention.

Figure 2 is a section along the line II—II of Fig. 1.

Figure 3 is a section along the line III—III of Fig. 1.

Figure 4 is a section along the line IV—IV of Fig. 1.

Figure 5 is a horizontal section along the line V—V of Fig. 4.

Figure 6 is a vertical section along the line VI—VI of Fig. 4.

Figure 7 shows a bolt used as fastening means for the rails.

Figure 8 shows a member of the fastening means.

Figure 9 is a transverse section through a modification of the railroad construction according to the invention.

Figure 10 is a transverse section through a second modification.

Figure 11 is a plan view of a railroad construction according to Fig. 10.

Figure 12 is a transverse section of a third modification.

Referring more particularly to Figures 1 to 8, 1 indicates a rail having in section the shape of a reversed U of which the upper part

has the profile of a head according to the usual railroad rails.

The adjacent ends of two consecutive rails meet on the tie 3. This tie supports the horizontal branches 4 of a supporting member 5 which is also of reversed U shape in section and on which member rest the two ends of the rails. Clamping plates 6 are disposed on both sides of the two rail ends and are placed with the edges 7 on the flanges 3 of the rails, while the edges 8 of the plates abut against the raised edges 9 of the supporting member 5.

B represents a fastening device which connects the tie 3, the supporting member 5 and the clamping plate 6. This device comprises a bolt 10 (Fig. 7) provided with a head 11 and with two lateral grooves 14a adapted to engage the two branches of the U shaped key 14 (Fig. 8). A strong helicoidal spring 12 is engaged between the key 14 and the plate 6.

In order to assemble the fastening device, the bolt 10 is inserted through corresponding holes in the three members to be clamped together and then the spring 12 is brought over the bolt. This spring before being compressed reaches over the two grooves 14a. By means of a tool which is not represented and which is engaged in the grooves 13 of the bolt and comprises a lever arm adapted to act on the spring 12, this spring is compressed and then the key 14 is inserted in the grooves 14a, whereupon the tool is removed. The spring 12 then exerts pressure between the plate 6 and the key 14 whereby the rail 1 is firmly secured to the tie. A projecting cap 14b may be placed over the key 14 and spring 12.

The tie 3 is provided with two apertures 17 engaging each projection 16 of the supporting member 5 in order to prevent this member from any unintentional sliding movement on the tie. The supporting member 5 is also provided with two longitudinally extending raised portions 18 against the inner edge of which the flange 3 of the rail abuts in order to prevent the two web portions 2 of the rail from spreading apart.

Between two ties 3 to which the ends of a

rail are secured, the rail is fixed to alternate ties *a* by means of a similar device as above described and comprising the clamping plates 6, supporting member 5 and fastening device

5 B. On alternate ties *c* the rail is supported by a tie plate 19 having two raised edges 20 and which plate is fixed to the tie *c* by means of a fastening device B as above described.

It could happen that one has to connect a 10 track formed of ordinary T rails to a track composed of rails according to this invention. This case is illustrated on the right hand side of Figure 1 and in Figs. 4, 5 and 6. The rail joint is supported by a sleeper of double 15 width *d*. The end of a short section of T-rail 15 is deprived of its head C over a length 1 and penetrates into the interior of the rail 1 between the two branches of a supporting member 21 similar to the member 5 above 20 described. Clamping plates 24 rest on the flanges 3 of the rail 1 and the foot D of the T-rail 15 and abut on the edges 9 of the supporting member 21. The clamping plates 24 and the member 21 are secured to the tie *d* 25 by means of fastening devices B as above described. Fish plates 25 and 26 are disposed on both sides of the two railends to be joined and are suitably bent at 27 in order to coact with the webs 2 of the rail 1 and with the 30 web 22 of the rail 15.

In the modification according to Figure 9 wooden ties *e* are used. The bolts 10 of the fastening devices B which secure the clamping plates 6, the supporting member 5 and the tie plate 31 to the tie *e* traverse the tie; a washer plate 30 is inserted between the heads 11 of the bolts and the tie. The tie plate 31 is also provided with apertures 17 engaging projections 16 of the supporting member 5.

In the modification according to Figures 10 and 11, the bolts 10 have their heads 11 engaged beneath the tie plate 32 which is secured to the tie *e* by means of wood-screws 35. In this construction first the tie plate 32 with the bolts 10 is placed on the tie and the screws 35 are screwed home with their heads turned into the position as shown in Figure 10. Then the supporting member 5 is placed 50 over the bolts 10 and the rail 1 is placed over the U-shaped portion of the member 5. Finally the clamping plates 6 are placed over the bolts 10 and the fastening device B is assembled. It is now not possible for the 55 screws 35 to get loose since the supporting member 5 prevents the screw head from turning.

In the modification shown in Figure 12, the supporting member 37 is provided with 60 longitudinally extending grooves 38 which are obtained by pressing the material so that corresponding projections 39 are formed on the lower face of the supporting member 37.

The grooves 38 are adapted to receive the 65 edges 40 of the flanges 3 of the rail 1, while

the projections 39 are engaged by grooves 41 provided in the tie 45. The clamping plates 6 and the supporting member 37 are again secured to the tie 45 by means of fastening devices B.

If a track formed of rails according to this invention is used for electric traction, the ends of two consecutive rails can be electrically united by means of a copper conductor 42 disposed between the head of the rail 1 and the supporting member 37. The conductor 42 has its two ends 43 bent downwardly and inserted into vertical openings 44 provided in the supporting member 37.

I claim:

1. In a railroad construction, in combination with ties and rails supported thereon, said rails having in transverse section the shape of a reversed U, a connecting device for adjacent ends of consecutive rails including a supporting member having in transverse section the shape of a reversed U and having horizontal flange portions seated on the tie, said rails having two lateral flanges placed on said member, clamping plates lying on said flanges and said supporting member on opposite sides of each rail, and fastening means for yieldingly locking the clamping plate, the supporting member and the tie together.

2. In a railroad construction, in combination with ties and rails supported thereon, said rails having in transverse section the shape of a reversed U, a connection device for adjacent ends of consecutive rails including a supporting member having in transverse section the shape of a reversed U and having horizontal flange portions seated on the tie, the rails being placed over the supporting member and having two lateral flanges seated on said horizontal flanges of the supporting member, clamping plates lying on said flanges and on said supporting member on opposite sides of each rail, a bolt traversing the clamping plate, the supporting member and the tie, a key engaged in the upper end of said bolt and a spring placed over the bolt between said key and the clamping plate.

3. In a railroad construction, in combination with ties and rails supported thereon, said rails having in transverse section the shape of a reversed U, a rail supporting member placed on alternate ties, said rail supporting member having in transverse section the shape of a reversed U and being provided with horizontal flange portions seated on the tie, said rails being provided with lateral flanges seated on said horizontal portions of the rail supporting member, clamping plates lying on said rail flanges and on said rail supporting member, a bolt traversing the clamping plate, the supporting member and the tie, a key engaged in the upper end of said bolt, and a spring placed

over the bolt between said key and said clamping plate.

4. In a railroad construction, in combination with ties and rails supported on the ties, said rails having in transverse section the shape of a reversed **U** and including a head, two web portions and two lateral flanges, a tie plate carried by each alternate tie and supporting said flanges, and resilient fastening means for securing the tie plate to the tie, said fastening means including a bolt traversing the tie and the tie plate and extending between the two web portions of the rail, a key engaged on the bolt and a spring inserted between the key and the tie plate.

5. A railroad construction comprising rails having in transverse section the shape of a reversed **U** and including a head, two web portions and two lateral flanges, a rail supporting member placed on the ties and having in transverse section the shape of a reversed **U** extending between the two web portions of the rail, clamping plates lying on the flanges of the rail and on the rail supporting member, and resilient fastening means for locking the clamping plate, the rail supporting member and the tie together.

6. A railroad construction comprising rails having in transverse section the shape of a reverse **U** and including a head, two web portions and two lateral flanges, a rail supporting member placed on the ties and having in transverse section the shape of a reversed **U** extending between the two web portions of the rail, an electric conductor placed between the rail and the rail supporting member and electrically connecting the adjacent ends of consecutive rails, clamping plates lying on the rail supporting member and on the flanges of the rail, and resilient fastening means locking the clamping plate, the rail supporting member and the tie together.

In testimony whereof I affix my signature.

EUGÈNE BRANDT.
